Attorney

UNITED STATES PATENT OFFICE.

FRANK E. KARG, OF YOUNGSTOWN, OHIO.

ELECTRIC HEATER.

1,316,161.

Specification of Letters Patent. Patented Sept. 16, 1919.

Application filed September 17, 1918. Serial No. 254,386.

To all whom it may concern:

Be it known that I, FRANK E. KARG, a citizen of the United States, residing at Youngstown, in the county of Mahoning and State of Ohio, have invented certain new and useful Improvements in Electric Heaters, of which the following is a specification.

This invention relates to heating appliances, and more particularly to those heated by electrical resistance, that is resistance offered to the passage of an electric current through a resistance element designed to produce heat.

The primary object of the invention is to provide an electrical heater which is in the form of a furnace having means for forcing air through the same and for effectively heating said air, said device being capable of being readily taken apart for cleaning or repair.

With the above and other objects in view, as will appear as the description proceeds, the invention comprises the various novel features of construction and arrangement of parts which will be more fully described herein and set forth with particularity in the claims appended hereto.

Reference is had to the accompanying drawings forming a part of this application, in which like reference characters indicate the corresponding parts throughout the several views, in which—

Figure 1 is a vertical sectional view of my improved electrical heater or furnace, and

Fig. 2 is a horizontal sectional view taken on the line 2—2 of Fig. 1.

Referring to the drawings in detail, my improved electrical heater is shown as comprising a cylindrical drum or body 10 supported upon the floor in a dwelling or cellar, depending upon the size of the device and its capacity for heating. The upper end of the cylindrical body portion 10 is provided with a flange 11 serving for detachable connection of a frusto-conical or dome like top portion 12 having mounted in the upper end thereof, through the medium of a cross brace 13 an electric motor 14 carrying a fan 15, the circuit wires for the motor being designated at 16 and the fan being designed to suck or draw air into the furnace when rotated, the quantity of air depending upon the speed of rotation of the fan.

Fitted within the furnace body is a partition or head 17, the same being of funnel

or hopper-like form and having a flange 18 which in conjunction with a flange 19 formed at the lower portion of the frusto-conical or dome-like top 12, is designed to be bolted to the flange 11, as through the medium of bolts or other securing means 20. It is of course understood that any preferred means may be provided for detachably supporting the head or partition member 17 within the furnace body produced by the sections 10 and 12 constituting upper and lower sections of the furnace. It will also be understood that this connection provides means for readily taking the parts down or separating them, so that they may be readily cleaned or repaired, when occasion should require.

The partition or head 17 is provided with a depending tubular portion 21 axially located with respect thereto and is further provided outwardly and beneath the same, supported upon the plurality of depending hangers 22, an insulating ring 23 carrying a plurality of heating coils 24 and branching outwardly from the body 10 adjacent thereto, are a plurality of heating pipes 25, the same extending radially and upwardly and extended to the desired rooms or parts to be heated, or in a small furnace, simply to the room in which the heater is located. Thus it will be seen that when air is forced downwardly to strike the head 17, it will be heated owing to the coils 24 but the air will further pass through the baffle member or tube 21, and then pass upwardly around the heated coils and out through the outlet pipes 25, thus providing a tortuous path through which the air will circulate in passing through the furnace during the heating operation, thereby insuring a constant supply of fresh air in a heated space at all times. The coils 24 are connected in circuit with a suitable source of electrical energy, the circuit wires or conductors thereof being designated 26 and 27 respectively.

From the foregoing description taken in connection with the accompanying drawings, it is thought that a clear and comprehensive understanding of the construction, operation, and advantages of my invention may be had, and while I have shown and described the device as embodying a specific structure, I desire that it be understood that such changes may be made in said structure as do not depart from the spirit and scope of the invention as claimed.

Having thus described my invention what I claim is new, and desire to secure by Letters Patent, is:

- 5 1. An electrical heater comprising a lower body portion and an upper portion detachably connected thereto, a fan at the upper portion adapted to force air into the same, a partition mounted between said top and bottom portions and having a depending 10 tubular member through which air is forced under pressure from the fan, heating members carried by said partition, and outlet pipes for the furnace body below the partition.
- 15 2. An electrical furnace comprising a lower cylindrical portion, a frusto-conical

top portion having an opening in the upper end thereof and detachably connected to the lower portion, a funnel-like head supported within said furnace body produced 20 by said upper and lower portions, and having a depending axial tube, a fan supported in said top opening of the frusto-conical section to force air downwardly through said tube after striking the baffle wall thereof, 25 said baffle wall sloping downwardly, a plurality of electrical heaters suspended from said partition and a plurality of outlet pipes leading from said body adjacent thereto.

In testimony whereof, I affix my signature 30 hereto.

FRANK E. KARG.
